COVE MOLDING FOR TILE CEILINGS OR THE LIKE

Edgar A. Lauring, International Falls, Minn., assignor to Minnesota and Ontario Paper Company, Minneapolis,
Minn.

Filed June 14, 1962, Ser. No. 70,541

Term of patent 14 years

(Cl. D13—6)

The FIGURE is a perspective view of a cove molding for tile ceilings or the like, showing my new design.

I claim:

The ornamental design for a cove molding for tile ceilings or the like, substantially as shown.
